CLAIM

We claim the ornamental design for a chromatograph, as shown and described.

DESCRIPTION

FIG. 1 is a front perspective view of a chromatograph. FIG. 2 is another front perspective view of the chromatograph illustrated in FIG. 1.

FIG. 3 is a rear perspective view of the chromatograph illustrated in FIG. 1.

FIG. 4 is a front elevation view of the chromatograph illustrated in FIG. 1.

FIG. 5 is a right side elevation view of the chromatograph illustrated in FIG. 1.

FIG. 6 is a rear elevation view of the chromatograph illustrated in FIG. 1.

FIG. 7 is a left side elevation view of the chromatograph illustrated in FIG. 1.

FIG. 8 is a top plan view of the chromatograph illustrated in FIG. 1; and,

FIG. 9 is a bottom plan view of the chromatograph illustrated in FIG. 1.

In the drawings, the broken lines illustrate portions of the chromatograph that form no part of the claimed design.
